PORTABLE CONCRETE BATCHING AND
MIXING TRUCK

Guy H. Strayer, Erie, Pa.

Application February 26, 1940, Serial No. 320,747

9 Claims. (Cl. 259—153)

This invention relates generally to concrete batching and mixing plants and more particularly to a portable concrete batching and mixing truck.

All plants of this character made according to the prior art and with which I am familiar, have been stationary plants. Mixers are being used on trucks but no combined portable batching and mixing plant has ever been designed to move over a highway. All of the prior plants required rehandling of materials and where it was necessary to haul the mix in trucks, the operation was costly and the capacity necessarily limited. No batching unit has heretofore provided any efficient means for pre-mixing the aggregates and the cement.

It is accordingly an object of my invention to provide a portable concrete batching and mixing truck of predetermined height, length, and width wherein it can move over any highway in the United States within highway clearance regulations of any State thereof.

Another object of my invention is to provide a portable concrete batching and mixing truck wherein the mixer, aggrerometer, elevator, and bin are so located that the most efficient operation of the machine can be obtained while locating the center of gravity of the truck at the center thereof to maintain balance.

Another object of my invention is to provide an underframe for a concrete batching and mixing truck which has an upwardly off-set portion at its forward end to permit the machine to turn in a limited area.

Another object of my invention is to provide a batching and mixing truck for concrete wherein the sides of the bin are foldable to minimize the height of the machine.

Another object of my invention is to provide an elevator on a portable concrete batching and mixing truck which is pivoted centrally thereof to minimize the height of the truck when it is in transit.

Another object of my invention is to provide a portable batching and mixing truck which requires no rehandling of materials.

Another object of my invention is to provide a portable batching and mixing plant which is self-loading.

Another object of my invention is to provide a means in a batching and mixing unit for pre-mixing the aggregates and the cement before it reaches the mixer.

Another object of my invention is to provide a portable concrete batching and mixing truck

which may be made ready for movement and which may be set up in operative position in a minimum of time.

Another object of my invention is to provide a portable concrete batching and mixing plant which requires the minimum amount of labor for successful operation.

Another object of my invention is to provide a portable concrete batching and mixing plant wherein all controls for weighing, mixing and discharging concrete may be operated from one point.

Another object of my invention is to provide a portable concrete batching and mixing truck with hoisting means operated by the same engine which operates all other units of the plant.

Another object of my invention is to provide a portable concrete batching and mixing plant which may be moved on a highway with an ordinary motor truck.

Another object of my invention is to provide a portable batching and mixing truck with a self-feeding elevator having a swivel chute leading to the bins movable through a limited arc and controlled from the central point of the truck.

Another object of my invention is to provide a portable batching and mixing truck which has ample storage space for aggregates.

Another object of my invention is to decrease transportation costs for a batching and mixing plant.

Another object of my invention is to provide a batching and mixing plant which provides quality concrete at the least possible cost.

Other objects of my invention will become evident from the following detailed description, taken in conjunction with the accompanying drawings, in which

Fig. 1 is a side elevational view of my novel portable concrete batching and mixing truck in operative position.

Fig. 2 is a side elevational view of my novel portable concrete batching and mixing truck in position for movement over a highway.

Fig. 3 is a rear end view of my novel portable concrete batching and mixing truck in operative position.

Fig. 4 is a fragmentary side elevational view in section showing the weighing hopper or aggrerometer and the cement hopper with the common feeding screw passing therebeneath.

Fig. 5 is a perspective view of the swinging gate for the weighing hopper or aggrerometer.

Fig. 6 is a fragmentary plan view of the engine and drive mechanism for the various units of

my novel portable concrete batching and mixing truck.

Fig. 7 is a diagrammatic view of the connecting drives when the hoist is in operative position in my novel portable concrete batching and mixing truck.

Fig. 8 is a diagrammatic view of the connecting drive when the feed screw for the mix is in operative position in my novel concrete batching and mixing truck.

Referring to the drawings, Figs. 1 to 3 show the general framework of my novel concrete batching and mixing truck comprising an underframe 1 with an upwardly off-set portion 2, integral supporting columns 3 and 4, and longitudinal and transversely disposed beams 5 and 6, all of which is suitably braced by bracing members 7. Wheels 8 and 9 on axles 10 and 11 support the underframe 1. Pneumatic tires 12 are preferably disposed on the wheels 8 and 9 in order that my novel truck may move over highways without injury thereto and in the fastest time interval. The forward axle 10 is on a swivel 13 in order that the truck may turn in a limited space, the upwardly projecting portion 2 of the underframe 1 permitting the wheels 8 free clearance thereunder. The framework is preferably welded although it will be understood that any form of construction may be utilized.

A drum-type concrete mixer 14 is supported on rollers 15 centrally of the underframe 1 and to one side thereof so that the discharge gate 16 projects outwardly from the side of the framework sufficiently to permit the ready filling of concrete buggies and the like. The mixer 14 is rotated through a centrally disposed rack 17 in engagement with gear 18 empowered through a transmission 19 shown in Fig. 6 by a gasoline engine 20 or any other suitable prime mover disposed on the forward part of the underframe 1. The gate 16 is operated through a control wheel 95, sprocket chain 96 and a sprocket wheel and linkage system 97.

A bin 21 is disposed above and on the opposite side of the mixer 14 on the top side of the frame. The bin 21 has sides 22 and ends 23 which fold inwardly to a position shown in Fig. 2, to minimize the height of the truck. The bin 21 may be provided with one or two partition members 24 which also are foldable inwardly as shown in Fig. 2. The lower portions 25 and 26 of the bin 21 recede into outlets 27 and 28 on the side opposite to that on which the mixer 14 is mounted. Rolling-type gates (not shown) in the outlets 27 and 28 are operated by hand wheels 29 leading to the operator's platform 30 on the rear of the underframe 1. The rolling-type gates in the outlets 27 and 28 may be power operated.

A weighing hopper or aggremeter 31 is disposed under the outlets 27 and 28 of the bin 21 on the side of the underframe 1 opposite to that of the mixer 14 so that all aggregates from the bin 21 may be weighed before passing to the mixer 14. The scales 32 for weighing the aggregates are operable from the operator's platform 30. The aggremeter 31 is provided with partitioning members (not shown) in order that the different aggregates from the outlets 25 and 26 may be placed in separate compartments in the aggremeter 31, and therefore mixed uniformly when they leave the aggremeter 31. A cement hopper 33 is disposed adjacent to the aggremeter 31 and it has an outlet which allows the cement to be fed to the mixer 14 by means of a helical

feed screw 34 (Fig. 4) which passes under the outlet of the aggremeter 31 to the inlet spout 35 of the mixer 14. A swinging radial-type gate 36 (Fig. 5) controls the flow of aggregates from the outlet of the aggremeter 31 and it is operated by a foot lever 37 operable from the operator's platform 30. This foot lever 37 also operates a clutch 38 from the foot lever shaft 39 through connected levers 80 and 81, which transmits power to the feed screws 34. It will be evident therefore, that the feed screw 34 will be operated only during the time that the swinging gate 36 is open thereby providing for a dry premixing of the cement being fed forwardly to the mixer 14 by the feed screw 34 with the aggregates coming to the feed screw 34 from the outlet of the aggremeter 31. A standard batchmeter 83 to insure uniform mixing is operated through the lever 84 from shaft 39, upon which the foot lever 37 is mounted. The amount of aggregates in proportion to the amount of cement may be controlled by the amount of opening of the swinging gate.

An elevator casing 40 is pivoted to the side of the frame opposite to the mixer 14 at 41 by any suitable pivoting means. A bucket-type elevator 42 is disposed in the casing 40. The casing 40 has an opening 43 in the bottom portion thereof for receiving aggregates from a truck hopper 44 and the upper portion of the casing 40 has an outlet 45 leading into a swiveled chute 46 swingable about its point of suspension 47 to direct the aggregates to the compartment in the bin 21 which is desired. A shaft 48 operated by a cable 49 leading to the operator's platform 30 through suitable sheaves 50 permits the swinging of the chute 46 through a limited arc from the operator's platform 30 by means of the crank lever 85.

The mixer 14, bucket elevator 42, and the feed screw 34 are all empowered by the engine 20 through suitable gears 51 and 52 on shafts 53 and 54 and sprocket chains 55 and 56. Jaw clutches 57 and 58 are operated by handles 59 and 60 to rotate the mixer 14 and the bucket elevator 42. The feed screw 34 is rotated through clutch 38 operated from the foot lever shaft 39 when the swinging gate 36 on the aggremeter 31 is open.

The elevating buckets 42 are driven through the gear 61 on the shaft 53 by a sprocket chain 62 connecting the sprocket wheel 63 on the shaft 86 of the bucket elevators' pulley 87. An idler 64 prevents excessive play in the sprocket chain 62. This connection is diagrammatically shown in Fig. 8. The sprocket chain 62 is removed when the truck is in transit. Braking means 100 is provided to control the elevating buckets 42.

Fig. 7 shows the connection of a sprocket chain 66 to a hoisting drum 65 on the same shaft as the feed screw 34. This connection is made when the elevating buckets 42 are not in operation to provide hoisting means for the elevator casing 40. The hoisting drum 65 is also used to hoist the truck hopper 44 and the ramp 67 by means of a boom 68 and suitable block and tackle 69 and 70 shown in Fig. 1 on the forward end of the truck frame. It will be evident that this boom 68 may be used for any purpose for which it is designed. The hoisting drum 65 may also be used for any purpose for which it is designed.

A hand brake 71 is provided for the rear wheels 9 although any form of suitable braking means may be provided. Generator and lighting equipment may be provided.

A water tank 88 is disposed in the upper forward portion of the frame with lines 89 and 90 leading directly to the mixer 14. Water control means lead to the operator's platform 30 and are controlled by water control member 91.

I will now describe the change-over of my novel concrete batching and mixing truck from operative to inoperative position and vice versa. Fig. 2 shows the truck in condition for transit over any highway in the United States with the elevator casing 40 lowered to a horizontal position and the sides 22, ends 23, and partition 24 of the bin 21 folded inwardly to an absolutely horizontal position. The maximum width of the truck in transit is eight feet with a maximum height of twelve feet six inches. It is pulled by a suitable drawbar 94 attached to a conventional motor truck 92. My novel truck may be placed in condition for transit from an operative position shown in Fig. 1 in less than thirty minutes.

To change the truck from a transit position shown in Fig. 2 to an operative position shown in Fig. 1, the time required is less than one hour. The truck is placed in its desired position in close proximity to the job at hand and the hoisting drum 65 is connected to the transmission 19 as shown in Fig. 7. The engine 20 is started and one strand of the block and tackle 93 attached to the bottom portion of the elevator casing 40 is wound around the hoisting drum 65 whereupon the elevator casing 40 is pulled to a vertical position as shown in Fig. 1 and secured by any suitable means. The Chicago boom 68 on the forward end of the truck is then utilized to place in position relative to the opening in the bottom of the elevator casing the truck hopper 44 and the ramp 67 whereby a motor truck 92 can dump into the truck hopper 44 as shown in Fig. 1 with the least amount of effort expended. The truck hopper 44 and the ramp can be carried in the motor truck 92 towing my novel concrete batching and mixing truck. The sprocket chain 66 for the hoisting drum 65 is then removed and the sprocket chain 62 for operating the elevating buckets 42 is connected to the transmission 19 as shown in Fig. 8.

The sides 22, ends 23 and partition or partitions 24 in the bin 21 is then raised to a vertical position, with suitable rods and braces provided to maintain them in this position under load. The side of the bin adjacent the elevator casing 40 is usually connected to the casing 40 thereby maintaining the elevator casing 40 in a vertical position as well as the side 22 of the bin 21. The clutches 57 and 58 for the elevator buckets 42 and the mixer 14 are then placed in operative position and the operations of batching and mixing concrete is ready to commence. Jacks or shoring (not shown) are ordinarily placed beneath the underframe 1 to take the load off of the wheels 8 and 9 during the operation of the batching and mixing unit. The operator, after placing the clutches 57 and 58 for the elevator buckets 42 and the mixer 14 in operative position, mounts the operator's platform 30 and places the aggregates which are dumped into the truck hopper 44 and elevated to the pin 21 in the proper compartment through cables 49 which lead to a crank lever 85 on the side of the frame adjacent the operator's platform 30. The desired amount and weight of aggregates are then allowed to flow to the aggremeter 31 through operation of control gate wheels 29 and the aggregates are properly weighed with the two or three beam scale 32. A predetermined amount of cement is then

dumped into the cement hopper 33 whereupon the foot lever 37 is operated to open the swinging gate 36 on the aggremeter 31 and engage the clutch 38 which operates the feed screw 34 to move the cement forwardly toward the inlet spout 35 of the mixer 14. It will be evident that a premixing of the aggregates and the cement will take place before they reach the mixer 14. The aggregates are placed in separate compartments in the aggremeter 31 to obtain a thorough mix of all aggregates and cement at the outlet of the aggremeter 31. A predetermined amount of water is added to the mix from the water tank 88 and waterpipes 89 and 90 through a suitable control lever 91 leading to the operator's platform 30. After the concrete is thoroughly mixed in the mixer 14, it is allowed to flow through the discharge spout thereof to a chute or concrete buggy or the like by opening the gate 16 from the operator's platform by rotation of the wheel 95 which in turn is connected to the discharge gate 16 through a sprocket chain 96, sprocket wheel and linkage 97. The same operation can then be repeated as often as desired. It will be evident that all necessary controls for the mixing of the concrete and discharge thereof is operable from the operator's platform 30, therefore requiring a minimum number of men for the operation of the batching and mixing machine. To place the truck in a condition for transit, the above procedure is reversed. It will be evident that one man can operate this plant except for the handling of the cement.

It will be evident from the foregoing description that I have provided a novel portable concrete batching and mixing truck which may be transported over any highway in the United States, which reduces transportation expenses to a minimum, which produces quality concrete at the least possible cost, which requires a minimum number of men to operate it, which requires a minimum amount of time to set-up for operation and to prepare for transit, and which provides a means for pre-mixing aggregates and cement before reaching the inlet spout of the mixer.

Various changes may be made in the specific embodiment of the present invention without departing from the spirit thereof, or from the scope of the appended claims.

What I claim is:

1. In a concrete batching and mixing plant in combination, a concrete mixer, an aggregate hopper, a cement hopper adjacent said aggregate hopper, a gate on the outlet of said aggregate hopper, a feeding screw for feeding cement from said cement hopper to said mixer, said cement and the material from said aggregate hopper being mixed before reaching said mixer, and means controlled by the movement of said gate to operate said feed screw while said gate is in an open position.

2. In a concrete batching and mixing plant in combination, a mixer, an aggregate hopper having a plurality of compartments, a cement hopper adjacent said aggregate hopper, a gate on the outlet of said aggregate hopper controlling the material moving from said compartments of said aggregate hopper, a feeding screw for feeding cement toward said mixer and in the path of the aggregates moving outwardly from said aggregate hopper when said gate is in an open position and means controlled by the movement of said gate to operate said screw while said gate is in an open position.

3. In a portable concrete batching and mixing truck for high speed movement over any highway having minimum height, width, and length and a low center of gravity, in combination, a frame, wheels for said frame, a concrete mixer disposed on one side of said frame, a bin disposed above and on the opposite side of said frame, an aggrometer disposed below said bin, means for premixing and for feeding material from said aggrometer and cement to said mixer, elevating means for conveying material to said bin pivoted centrally thereof to said frame opposite to said concrete mixer, said concrete mixer, bin, aggrometer, and pivoted elevating means being in substantial balance, and means for empowering said mixer, said feeding means for said mixer, and said elevating means.

4. In a portable concrete batching and mixing truck for high speed movement on any highway with minimum height, width, and length, and having a low center of gravity, in combination, a frame, wheels on said frame, braking means for said wheels, a concrete mixer disposed on one side of said frame, a bin disposed above and on the opposite side of said frame, an aggrometer disposed below said bin, means for premixing and for feeding material from said aggrometer and cement to said mixer, centrally pivoted conveying means for feeding material to said bins, said concrete mixer, bin, aggrometer, and conveying means being in substantial balance, power means for empowering said mixer, said feeding means and said conveying means, and means for controlling all of the operations of said mixer, aggrometer, conveying means, and braking means from a central point on the said truck.

5. In a portable concrete batching and mixing truck for high speed movement on any highway, and within standard height, width, and length limitations for vehicles, in combination, a frame, wheels for said frame, a concrete mixer disposed on one side of said frame, a bin disposed above and on the opposite side of said frame having the sides thereof foldable downwardly, an aggrometer disposed below said bins, means for premixing and for feeding material from said aggrometer and cement to said mixer, an elevator centrally pivoted to the side of said frame opposite said concrete mixer, said mixer, bin, aggrometer and elevator being in substantial balance, and power means for empowering said mixer, said feeding means and said elevator.

6. In a portable concrete batching and mixing truck for high speed movement on any highway within standard height, width, and length limitations for vehicles, in combination, a frame, wheels for said frame, a bin having a partition disposed above and on the opposite side of said frame, the sides and partitioning members of said bin being foldable downwardly, a weighing aggrometer disposed below said bin, a cement hopper adjacent said aggrometer, means for premixing and for feeding material from said aggrometer and cement from said cement hopper to said mixer, an elevator pivoted centrally thereof on the side of said frame opposite to said mixer, said concrete mixer, bin, elevator, cement hopper and aggrometer being in substantial bal-

ance, and power means for empowering said mixer, said feeding means and said elevator.

7. In a portable concrete batching and mixing truck for high speed movement on any highway and within standard height, width, and length limitations for vehicles, in combination, a frame, wheels for said frame, braking means for said wheels, a concrete mixer disposed on one side of said frame, a bin having foldable sides disposed above and on the opposite side of said frame, a weighing aggrometer disposed below said bin, a cement hopper, means for premixing and for feeding material from said aggrometer and cement hopper to said mixer, a source of water supply, a control platform, control means operable from said platform for controlling all of the batching and mixing operations of said truck, an elevator pivoted centrally thereof on the side of said frame opposite said mixer controlled from said control platform, and power means for empowering said elevator, feeding means, and said mixer.

8. In a balanced portable concrete batching and mixing truck for high speed movement on any highway and within standard height, width, and length limitations for vehicles, in combination, a frame, wheels for said frame, a concrete mixer disposed on one side of said frame, a bin disposed above and on the opposite side of said frame having the sides and partition members thereof foldable downwardly, a weighing aggrometer disposed below said bin having an outlet adjacent said mixer for feeding aggregates thereto, a cement hopper disposed adjacent to said aggrometer, a feed screw disposed below said cement hopper for feeding cement to said mixer, the outlet end of said feed screw being disposed adjacent the outlet in said aggrometer to feed said cement into the path of aggregates flowing from said aggrometer, a completely intact elevator pivoted centrally thereof to the side of said frame opposite to said mixer for feeding aggregates to said bin, and power means for empowering said mixer, said feed screw and said elevator.

9. In a balanced portable concrete batching and mixing truck for high speed movement on any highway and within standard limitations for vehicles, in combination, a frame, wheels for said frame, a concrete mixer disposed on one side of said frame, a bin disposed above and on the opposite side of said frame, a weighing aggrometer disposed below said bin having an outlet opening adjacent said mixer, a cement hopper, a feed screw for feeding cement into the path of aggregates flowing from said aggrometer, the outlet end of said feed screw directing cement in the path of aggregates passing from the outlet in said aggrometer to the mixer, a completely intact elevator pivoted centrally thereof to the side of said frame opposite said mixer for conveying material to said bins, a hoisting drum, and unitary power means for empowering said mixer, said feed screw, said hoisting drum and said elevator, said aggrometer, bin, elevator, concrete mixer, and cement hopper being disposed in substantial balance on said frame.

GUY H. STRAYER.
